LAMP TUBE CHANGER

Asa O. Switzer, Melrose, Ohio

Application June 17, 1944, Serial No. 540,783

6 Claims. (Cl. 294—21)

This invention relates to improvements in a lamp tube changer suited for removal and replacement of illuminating lamps, such as the tubular fluorescent type, with respect to the fixtures in which the tubes are supported.

Fluorescent illuminating lamps of the tubular type are supported in fixtures in which the opposite ends are received and it is necessary that upon installing the tube in connection with its fixtures, that the tube be turned axially into a definite position relative to its supporting fixtures in order that its electric contactors be located properly within the fixtures for the usual electrical connections essential to lighting of the lamp.

Fluorescent tubular lamps are frequently installed at points far above the floor, and ordinarily, servicing lamps thus installed requires use of ladders to enable the attendant to approach the lamp where situated to effect its removal or replacement.

An object of the instant invention is to provide an equipment by which to enable the attendant, while standing on the floor, to make removals and replacements, of lamps in remotely located positions.

Another object of the invention is to afford a grapple by which to engage a tubular lamp, in conjunction with a mechanism by which to impart angular rotation of the lamp with respect to the axis thereof to effect its removal or replacement from a distant point.

A further object of the invention is to afford a manually operated rotor in conjunction with grapple members by which to engage and hold a tubular lamp into contact with the rotor, so that upon engagement with the lamp and movement of the rotor, the lamp is turned about its axis therefore to permit removal or replacement of the lamp with respect to its supporting fixtures.

And a further object of the invention is to afford a tubular lamp provided with indicia thereon so located with respect to its electrical contactors that turning of the lamp about its axis relative to its supporting fixtures definitely indicates a proper angular position of the lamp for insertion into its supporting fixtures, and for contacting of its electrical connection with respect thereto.

Other objects and advantages of the invention appear in the following description.

An illustrative embodiment of the invention is shown in the accompanying drawings, in which—

Fig. 1 is an end elevational view of a grapple structure in which the invention is incorporated, a portion being broken away;

Fig. 2 is a fragmentary elevational view of the supporting pole for the grapple and an operating member in connection therewith;

Fig. 3 is a fragmentary end elevational view of the invention in a modified form, drawn to a reduced scale; and

Fig. 4 is a front elevational view of the device including a portion of a lamp tube secured in operative position therein, portions being broken away.

The illustrative embodiment of the invention consists of a supporting pole, preferably tubular and formed of two or more jointed sections 5, 6 of different diameters. The uppermost section 6 has secured thereon a clamp 7 in which is held a cross-beam 8, preferably of tubular form. Upon each end of the beam is rigidly secured a standard 9 by means of a cap-screw 10 that is threaded in a plug 11 secured in the corresponding end of the beam.

In the standards 9 is mounted a tubular shaft 12 having turning movement therein, and upon said shaft is mounted, at a point adjacent the inner face of each standard, a grapple arm 13 secured thereon by a set screw 14. Each grapple arm 13 has an extension 15 that is connected with the lower part of the standard 9 by means of a tension spring 16, there being provided a hook 17 on the extension 15 and a stud 18 on the standard to which the respective ends of the spring are connected. Each arm 13 has a pendent part 19 having lugs 20 spaced apart from each other, and a stop 21 is secured in each standard, the inner end of which projects into the path of the stops, whereby swinging movement of the arms is limited in either direction.

A stationary grapple arm 22, an integral part of each standard 9, is arched oppositely with respect to the adjacent grapple arm 13, and preferably each grapple arm has mounted on its free end a pair of contact rollers 13' and 22' respectively for the purpose hereinafter described.

Upon the shaft 12 extending between the grapple arms 13 is rotatably mounted a secondary tubular shaft 23 upon the midportion of which is secured a ratchet wheel 24, and adjacent the ratchet wheel upon the secondary shaft is loosely mounted an actuating lever 25 provided with a pawl 26 pivoted as at 26', the free end of which has engagement with the ratchet wheel. A compression spring 27 is arranged between a lug 28 on the actuating lever 25 and the outer end of the pawl to sustain the pawl in engagement with the ratchet wheel.

The actuating lever has a rearward extension

29 to which is attached one end of a contraction spring 30 the opposite end of which is connected with a hook 31 secured to the pole member 6, by which the lever is sustained normally in its uppermost position. The outer end of the lever 25 has removably connected thereto a wire 32 that is strung through an opening 33 made in the pole down into which the wire extends, its lower end being connected to an operating sleeve 34 that telescopes the lower section 5 of the pole, there being a screw 35 secured in the sleeve and extending through an elongated slot 36 in the pole, wherefore to permit connection with the wire and limited axial movement of the sleeve. By this arrangement movement is imparted to the actuating lever about the axis of the secondary shaft 23 and consequent turning of the secondary shaft through the medium of the ratchet wheel and pawl.

Upon the secondary shaft 23 are mounted cylindrical rotors or drivers 37 each preferably consisting of a cylinder 38 provided with an exterior elastic covering constituting a grooved tread 39. The drivers are located on the secondary shaft 23 at points thereon between the movable grapple arms 13 and the ratchet mechanism, there being a spacer 40 disposed on the secondary shaft between the ratchet mechanism and the adjacent end of the corresponding driver to sustain the various parts in proper relative positions.

In Fig. 3 is shown a form of the invention in which grapple arms 41 and 42 are arranged in connection with each other as in the former instance. In this form the grapple arms are provided at their ends with inturned contact points 41'-42' that bear against the lamp tube 43 and function to hold the tube against the rotor 44. This form of the invention permits grasping of the tube by the grapple arms more readily when the lamp is confined restrictedly in its fixtures (not shown).

Turning of the lamp permits the lamp terminals 45 to be positioned properly for insertion into the lamp fixture into contact with its electrical connections (not shown). Or, to be moved to proper position for removal of the lamp. The appliance is removed from the lamp tube by simply pulling upon the post with sufficient force to cause the grapple arms to spread apart and permit the tube to pass from between the rollers.

Operation

In using the invention, the tube 43 of the lamp to be installed in its fixtures or removed therefrom is grasped between the grapple arms which are placed astride the midportion of the tube. This is accomplished by manipulation of the pole so that the rollers are pressed against the tube with sufficient force to cause the grapple arms 13 to spread away from the stationary grapple arms 22 in opposition to restraint of the spring 16 so that the tube 43 rests upon the treads 39 of the rotors 37 due to the reactionary force of the springs 16. The grapple arms 13 swing inwardly causing the tube of the lamp to bear against the treads of the rotors, and against the rollers 22 on the stationary grapple arms 22. While the tube is thus grasped, by manipulation of the sleeve 34, movement is imparted to the operating lever 25 through the medium of the pull wire 32, causing the lever to swing downwardly in opposition to restraint of the spring 30 upon the down stroke of the sleeve, thus imparting movement of the rotors through the medium of the pawl and ratchet wheel. In this manner the

lamp tube is caused to turn upon its axis to a corresponding extent.

For guidance of the operator while installing and removing the lamps from their fixtures, indicia of any suitable character, such as may readily be seen at a distance, are superimposed upon the circumferential faces of the lamps in selected positions thereon to form markers 46-46'. These preferably are located at definite points relative to the lamp terminals 45 so their position, as the lamp is turned upon its axis, is indicated. If desired, the markers 46 are located at diametrically opposite points on the tube, while the other markers 46' are located in another plane that intersects the lamp terminals or at right angles to the plane of the other markers. To distinguish the one pair of markers clearly from the others, they are of different colors, thus to enable the operator to turn the tube angularly with respect to its axis to the best positions for insertion of the lamp into its fixture and adjusting it into its proper position for operation. The markers also serve, as the lamp is rotated, to indicate when the terminals reach proper positions for removal of the lamp.

Variations from the particular construction above disclosed may be resorted to by the exercise of skill in the art, without departure from the scope of the invention, and the following claims are intended to be inclusive of such variations.

What I claim is:

1. In an appliance for replacing tubular lamps, a tubular post having secured on its upper end a cross-beam, a standard secured on each end of said beam, a shaft the ends of which are supported in said standards for turning movement relative thereto, grapple arms secured to said shaft adjacent said standards having limited movement and provided with tension means to hold same in operative position, a tubular shaft mounted concentrically on the other shaft provided with a ratchet wheel, an operating lever mounted on the tubular shaft having relative movement thereto provided with a pawl engaging said wheel and having a tension means to hold the lever in its initial operating position, cylindrical drivers provided with elastic treads secured concentrically upon said tubular shaft, an operating sleeve concentrically disposed on said pole and longitudinally movable thereon, and a wire connected at one end with said sleeve and at its opposite end with the operating lever, a portion of said wire being confined within the pole, the upper ends of said standards and grapple arms having outwardly opposite curvature and provided at their upper ends with rollers, the arrangement being such that when a lamp tube is grasped by the appliance between the rollers and drivers the tube is turned as the drivers are rotated.

2. An appliance for replacing tubular lamps consisting of a frame including a cross-beam provided at its ends with rigid standards having arcuate extensions constituting stationary grapple arms, a shaft mounted in said standards for rotative movement having secured thereon spring-restrained arcuate grapple arms movable with the shaft and disposed oppositely with respect to the stationary arms, a secondary tubular shaft mounted concentrically on the other shaft for rotation thereon and provided with a ratchet wheel, a spring-restrained operating lever loosely disposed on the tubular shaft concentric therewith and provided with a spring-pressed

pawl engaging said wheel, a cylindrical driver secured on each end portion of the tubular shaft, a pole secured at one end to said cross-beam provided with a longitudinally movable sleeve on its opposite end portion, and a connection between said sleeve and lever, said arms being adapted to clasp a lamp tube against said drivers.

3. In an appliance for replacing tubular lamps, a frame consisting of a cross-beam and standards secured to the ends of the beam, having arcuate extensions constituting grapple arms, spring-restrained grapple arms having pivotal support in the frame disposed opposite the other arms, cylindrical drivers mounted in the frame, ratchet mechanism including an actuating lever therefor to rotate the drivers, said lever having a spring to hold it in its initial operating position, a pole on one end of which the frame is supported, a movable sleeve on the opposite end portion of said pole, and a wire connecting said sleeve and lever, said grapple arms being adapted to yieldingly clasp a lamp tube against said drivers.

4. In an apparatus for replacing tubular lamps, a frame having relatively movable oppositely disposed grapple arms, tension means acting to hold said grapple arms in closed position, a driving member supported in said frame, ratchet mechanism for actuating said member, a pole supporting the frame on one end thereof, and a movable operating member on the opposite end portion of the pole having a connection with the ratchet mechanism to actuate the same, said grapple arms being adapted to receive therebe-

tween a lamp tube and clasp same against said driving member.

5. In apparatus for replacing tubular lamps, two pairs of oppositely disposed relatively movable grapple arms provided with a supporting frame, tension means tending to hold the opposed arms in closed position, a driving member mounted in said frame for rotary movement provided with actuating means therefor, a pole, on one end of which said frame has support, and operating means on the opposite end portion of the pole having operative connection with said actuating means, the arrangement being such that when a lamp is clasped against the driving member by said arms and said member is actuated, the lamp is turned upon its axis.

6. An apparatus for replacing tubular lamps, consisting of a frame having two pairs of relatively movable grapple arms, the outer ends of which have inturned lamp-engaging points, tension means tending to hold the opposed arms in closed position, a driving member rotatably mounted in the frame provided with actuating means therefor, a pole upon which the frame is supported, at one end thereof, and operating means movably mounted on the opposite end portion of the pole having a connection with said actuating means, the arrangement being such that when the grapple arms are placed astride the lamp tube and clasp thereby against the driving member, the tube is axially turned upon rotation of the driving means to a corresponding extent.
